(57) CLAIM

The ornamental design for a bottle, as shown and described.

DESCRIPTION

FIG. 1 is a perspective view of a bottle showing our new design;

FIG. 2 is a front view of the bottle of FIG. 1;

FIG. 3 is a rear view of the bottle of FIG. 1;

FIG. 4 is a side view of the bottle of FIG. 1, the opposite side being a mirror image thereof;

FIG. 5 is a top view of the bottle of FIG. 1;

FIG. 6 is a bottom view of the bottle of FIG. 1;

FIG. 7 is a perspective view of a second embodiment of the bottle of FIG. 1 showing our new design;

FIG. 8 is a front view of the bottle of FIG. 7;

FIG. 9 is a rear view of the bottle of FIG. 7;

FIG. 10 is a side view of the bottle of FIG. 7, the opposite side being a mirror image thereof;

FIG. 11 is a top view of the bottle of FIG. 7; and,

FIG. 12 is a bottom view of the bottle of FIG. 7.

The broken line showing in FIGS. 1 through 12 is for illustrative purposes only and forms no part of the claimed design.
